UNITED STATES PATENT OFFICE.

JOHN NOLL, OF NEW YORK, N. Y., ASSIGNOR TO CONTINUOUS RAIL COMPANY, OF WILMINGTON, DELAWARE, A CORPORATION OF DELAWARE.

MACHINE FOR WORKING ON COMPOUND RAILS.

1,080,651.

Specification of Letters Patent.

Patented Dec. 9, 1913.

Application filed May 20, 1912. Serial No. 698,607.

To all whom it may concern:

Be it known that I, JOHN NOLL, a citizen of the United States, and a resident of the borough of Brooklyn of the city of New

5 York, in the county of Queens and State of New York, have invented certain new and useful Improvements in Machines for Working on Compound Rails, of which the following is a specification.

10 The invention relates to machines for working on compound rails that comprise top and base sections held together by lips on one of the sections, which lips are bent into firm engagement with the other section.

15 One object of the invention relates to a machine comprising a movable support or resisting member, a pressing roller arranged to force the top section of a compound rail against the base section when the latter is

20 on the movable resisting member and opposing rotary tools arranged to engage the holding lips, which tools are located at the side portions of the rail, as it passes the pressing roller.

25 Another object of the invention is directed to the supporting of a base section of a compound rail on a movable resisting member, pressing the top section of the rail against the base section by a roller arranged

30 above the movable resisting member as the rail moves under said roller and simultaneously therewith bending the holding lips on one of the sections into engagement with the companion section by means of com-

35 pression rollers located at the sides of the rail, which rollers engage said lips.

A further object of the invention consists in constructing a machine with a horizontal reciprocating bed for supporting one section

40 of a compound rail, with a horizontal roller above the bed to press another section of the rail against the section supported on the bed as the rail is moved along with the bed and with opposing rollers to engage the hold-

45 ing lips at the sides of the rail. The pressing roller and the opposing rollers are preferably supported in a carriage which may freely slide in a direction transverse to that in which the table reciprocates.

50 As showing a specific embodiment of the invention reference is made to the drawings forming a part of this specification and in which—

55 Figure 1 is an end elevation of the machine partially broken away, showing oper-

ating tools in engagement with a compound rail in the machine. Fig. 2 is a side elevation of the machine with the compound rail therein.

The reference character A designates the 60 frame of the machine upon which is slidably mounted the horizontally movable table B. This table is reciprocated by the driving mechanism C, C', C², C³, similar to that used in ordinary planer construction. 65

The length of the movement of the table and the reversal thereof is controlled by any suitable stop mechanism b, b' and b² (see Fig. 2) which is also common in ordinary planer construction. 70

The frame A comprises the uprights A' and A² and the horizontal member A³ extending therebetween. This horizontal member A³ extends transversely over the table and is vertically adjustable relative 75 thereto by the gear connected screws D D.

The carriage E is slidably mounted on the transverse member A³ and can be moved along the latter by the screw F. This carriage may be provided with any suitable 80 means whereby it can be disengaged from the screw F, thus allowing it free movement in a direction transverse to the direction along which the table reciprocates.

Horizontally extending pressing rollers G 85 are located above the table to force the sections of the compound rail together when on the table. Thus it will be observed that the table serves as a movable supporting member to resist the thrust of the pressing 90 rollers G as the rail is moved thereunder. These pressing rollers are mounted on the carriage E. There are also mounted in movable bearings H opposing rotary tools or bending rollers K which engage the depending holding lips x x. The bearings H are pivoted to the frame at h' and are caused to approach each other and are held in the proper position relative to each other by means of the toggle links M M that extend 95 therebetween. These links are actuated from the hand wheel N through the shaft n', the worm n² which engages a worm wheel n³ on the screw n⁴, and the nut and pin n⁵ at the joint P of the links M M. 100

It will be noted that the rotary tools or bending rollers K K are located adjacent to the ends of the horizontal pressing rollers G, that the adjacent portions y y of the opposing working faces of the bending 110

rollers K K are located between the pressing rollers G and the movable table, and that these opposing rotary tools K K are located on opposite sides of the rail as it progressively 5 passes under the pressing rollers. The axes of the opposing tools or bending rollers K K preferably extend in a general vertical direction.

In operating the machine one section of 10 the rail is first placed on the table and is preferably secured thereto, although this is not always necessary. When one section is in place on the other section they are caused to move along together under the pressing 15 roller whereby the latter forces the sections together. While the sections are thus pressed the holding lips are engaged by the opposing bending rollers and then bent to find holding position as the rail moves along 20 therebetween. The purpose of having the carriage E freely movable is to permit the pressing rollers and the opposing rotary tools to adjust themselves relative to the work, in conformity with irregularities in 25 the rail itself, or with the rail when in faulty adjustment in the machine.

The machine described is provided with a table which causes the rail sections to be drawn along under the pressing roller and 30 between the opposing bending rollers, but it will be noted that the pressing roller and bending rollers could be caused to travel along the rail when held on a fixed bed.

The improvements set forth herein are not 35 limited to the precise construction, arrangement and method shown and described and they may be embodied in various forms and modifications without departing from the spirit and scope of the invention.

40 I claim as my invention:

1. In a device of the class described for working on compound rails, the combination of a longitudinally reciprocating bed, a 45 pressing means for engaging and forcing work toward the bed, and operating tools for engaging opposite sides of a work-piece as it passes under the pressing means, said operating tools being mounted on a head which is free to move parallel to the bed 50 and transversely relative to the bed when the tools are operating.

2. In a device for working on compound rails, the combination of a horizontally reciprocating bed, means for reciprocating the 55 same, pressing means located above the bed which forces the work-piece against the bed, and rotary compression rollers opposed to each other for engaging the sides of the work-piece as it passes under the pressing

means, said rollers being mounted on a head 60 that is free to move transversely of the bed when operating on the work-piece.

3. In a device for working on compound rails, the combination of a reciprocating table, a head freely movable in a direction 65 parallel to but transversely of the reciprocating table, said head carrying thereupon a pressing roller for forcing the work against the table and opposing rotary tools for engaging opposite sides of the rail passing under the pressing roller.

4. In a machine for working on compound rails, the combination of a reciprocating table serving as a holding and supporting member, a roller opposed thereto for forcing 75 the rail sections together when on the supporting member, and opposing bending rollers to engage the side portions of the rail, the supporting member and rollers so arranged that the side portions of the rail 80 can be progressively engaged by the bending rollers, the rollers being on shafts that are mounted in bearings on a head which is free to move transversely relative to the table when the rollers are operating.

5. A machine for working on compound rails comprising a frame supporting a horizontally and longitudinally movable reciprocating bed provided with work piece securing means thereupon, and a head which is 90 free to move horizontally and transversely relative to the bed, said head having a pressure roller whose axis extends horizontally and transversely relative to the bed and opposing rotary tools whose axes extend vertically and transversely relative to the bed 95 and which tools have work engaging portions arranged to engage the sides of the work piece as the sections constituting the rail pass under the pressing rollers and at 100 a time when one of said sections is secured to the bed by the securing means.

6. A machine for working on compound rails comprising a frame supporting a horizontally and transversely reciprocating bed 105 provided with work-piece securing means thereon and a head which is free to move horizontally and transversely relative to the bed, said head having vertically operating pressing means, and laterally opposed pressing means operating transversely of the bed.

This specification signed and witnessed this 14th day of May, A. D. 1912.

JOHN NOLL.
